DUAL WALL REGISTER

Lowell L. Smith, Tuckahoe, and Jervis J. Gennari,
Yonkers, N. Y., assignors to American Radiator
& Standard Sanitary Corporation, Pittsburgh,
Pa., a corporation of Delaware

Application December 30, 1950, Serial No. 203,689

6 Claims. (Cl. 98—104)

1

This invention relates to new and useful improvements in wall registers for warm air furnaces, and more particularly to a dual register for cooperation with a floor type furnace.

An object of this invention is to provide a register of simple construction which will be efficient in operation.

Another object is to provide a register for discharge of air in opposite directions as to the spaces on opposite sides of a room wall.

Another object is to provide a register having provision for return air flow from the rooms to the furnace.

Another object is to provide a register having air cooled spaces to protect the room wall from the heated air supplied to the register.

This invention consists in the improved construction and combination of parts to be more fully described hereinafter and the novelty of which will be particularly pointed out and distinctly claimed.

In the accompanying drawings to be taken as a part of this specification there is fully and clearly illustrated a preferred embodiment of the invention, in which drawings:

Figure 1 is a view in front elevation of a register embodying the invention and positioned in a room wall with the floor in section and showing a portion of the furnace casing.

Fig. 2 is a view in section on the line II—II of Fig. 1.

Fig. 3 is a view in section on the line III—III of Fig. 2.

Fig. 4 is a view in section on the line IV—IV of Fig. 2, and

Fig. 5 is a detailed plan view showing a portion of an air flow controlling damper and its lever operating mechanism.

Referring to the drawings by characters of reference, 1 and 2 designate adjoining rooms or spaces having a floor 3 and separated by a vertical room wall or partition 4. Centrally below the wall 4 the floor 3 has a rectangular opening therethrough in which is positioned a floor type air heating furnace of any of the usual constructions having a rectangular outer casing 5 with a surrounding outturned flange 6 which rests upon the peripheral portion of the floor surrounding the mentioned opening. Within the casing 5 there is a combustion chamber 7 and radiators 8 which are spaced from the casing 5 by a rectangular surrounding partition 9 having an inwardly converging continuous upper edge portion 10.

The register which seats on the furnace is

2

positioned in a rectangular opening through the wall 4 and has an inner casing 11, an outer casing 12, and a pair of grille supporting members 13 and 14 which house the opposite sides of the register.

The inner casing 11 has spaced vertical end walls 15, 16 with upward converging side edges. The end walls are joined by upper and lower top wall members 17, 18, respectively, having down-turned flanges spot welded or otherwise secured to the end walls. The upper and lower wall members 17, 18 are vertically spaced and inclined upwardly from their mid-portions toward the side edges of the end wall members 15, 16 to provide oppositely discharging air passageways extending from end to end of the inner casing. The lower side edge portions of the end walls 15, 16 are recessed and joined by side wall members 19, 20 which seat in the recessed portions and have end flanges 21 which overlap the end walls 15, 16 and are spot welded or otherwise secured thereto. The side wall members 19, 20 terminate at their upper horizontal edges in out-turned flanges which terminate in the respective planes of the side edges of the end walls 15, 16 above the recessed portions. The top edge flanges of the side wall members 19, 20, the end walls 15, 16 and the lower top wall member 18 define oppositely directed warm air discharge outlets 22, 23 from the inner casing 11. The side wall members 19, 20 each has a horizontal outward extending bottom portion 24 which overlies the end portions of the space within the furnace partition 10. The lower edge portions of the end walls 15, 16 terminate in downward and outward inclined flanges which seat on the furnace partition flange 10 and form a continuation of similar flanges extending downward from the side wall bottom portions 24, which last-named flanges also seat on the furnace flange portion 10. Through the end walls 15, 16 at points located between the upper and lower top walls 17, 18 there is a plurality of air inflow apertures 25 leading to the passageways between these members.

Air flow to the outlets 22, 23 may be selectively controlled by a plate type damper 26 which is pivoted on a shaft 27 extending horizontally between and through supporting apertures in the end walls 15, 16. The damper 26 has a spring pressed friction pin 28 which bears against the inside face of the end wall 15 to frictionally hold the damper 26 in adjusted position. Extending transverse to the plane of the damper 26 and secured thereto and apertured for passage

of the shaft 27 therethrough there is an arm 29 extending equally from opposite sides of the damper. Extending downward from each end of the arm 29 there is a pivoted link 30. These links 30 are pivoted at their lower ends respectively to oppositely directed damper operating levers 31, 32 which are pivoted respectively intermediate their ends on pivot pins 33, 34 which are fixed in and to the end wall 15. The upper edge portion of the damper 26 extends above the shaft 27 and swings within a concave or upwardly curved recess portion 35 in the lower top wall 18. The portion 35 also provides clearance space for the damper arm 29 and links 30, as indicated in dash lines, upon swinging of the damper. Clearance for the opposite end portions of the shaft 27 and reinforcing for the end walls 15, 16 is provided by vertical plate members 36 secured one to the outer face of each of the end walls 15, 16 and each of which has a vertical reinforcing angle member 37 abutting its respective end wall.

The outer casing 12 has vertical end walls 38, 39 which are spaced from the end walls 15, 16, respectively, and which are joined by a top wall 40 which is spaced above the upper top wall 17. The top wall 40 is reinforced by a channel member 41 which also extends between the end walls 38, 39 and has side flanges by which it is secured to the top wall 40, as by spot welding. The channel member 41 also serves to form with the top wall 40 and the end walls 38, 39 a dead air space underlying the horizontal portion of the wall 4 which overlies the register receiving opening. The lower edges of the end walls 38, 39 seat upon the furnace casing flange 6. The inner casing 11 is positioned endwise within the outer casing 12 by vertical partition members 42, which extend inward toward each other from the vertical center lines or mid-portions of the outer casing end walls 38, 39, the partition members 42 each having a flange 43 lying against its respective end wall and secured thereto by spot welding or the like. The partition members 42 each has its free inner edge portion recessed as at 44 to provide clearance for the ends of the shaft 27 and the inner casing end wall reinforcing members 36. The partition members 42 are joined above the inner casing top wall 17 by an angle member 45 having a horizontal flange spot welded or the like to the channel member 41 and having a vertical flange extending downward toward the top wall 17, this vertical flange and the partition members 42 cooperating to substantially block or materially reduce air flow from one side to the other of the outer casing around the inner casing. The grille supporting members 13, 14 which house the opposite sides of the register each has opposite end face portions 46 with vertical inner edges which seat against the opposite faces of the wall 4 at the sides of the register receiving opening therethrough. Each pair of end face portions 46 is joined by a top face portion 47 and a side face portion 48 which surrounds its grille receiving opening. Positioned in each of these grille receiving openings there is a grille member 49 having vertical or upright slot-like apertures therethrough. The grille member receiving openings extend laterally beyond the end walls 15, 16 of the inner casing member and to the end walls 38, 39 of the outer casing member so that these openings overlie or extend across the warm air discharge outlets 22, 23, registering therewith, and overlap the inlets to the passageways 50, 51 on opposite sides of the partition member 42 be-

tween the end walls 15 and 38 and also overlap the inlets to the passageways 52, 53 on opposite sides of the partition member 42 between the end walls 16 and 39. The grille members 49 have end groups of apertures or slots 54 through which return air from the rooms can flow to the passageways 50, 51, 52 and 53. Each of the grille members 49 also has a central group of slots or apertures 55 overlying the warm air outlets 22 and 23 for discharge of the warm air therethrough into the rooms on opposite sides of the wall 4. Each of the grille receiving members has vertical flanges 56, 57 extending one from each side edge of the grille receiving opening. The flanges 56, 57 overlap and laterally engage the outside faces of the side edge portions of the end walls 38, 39, respectively. The flanges 56, 57 are adjustably secured for horizontal movement to the end walls 38, 39 by bolts 58 passed through apertures in the flanges 56, 57 and slidably laterally in horizontal slots 59 in the end walls 38, 39. The bottom edges of the side face portions 48 are preferably recessed between their ends as at 60 (see Fig. 4) to provide receiving spaces for the horizontal floor grids or grilles 61 which seat at their three outer edges on the floor 3 in overlying relation to the return air downflow space between the furnace casing 5 and partition 9. The grilles 61 also overlie the inner casing bottom portions 24 and have their inner edges extending substantially to the inner casing side walls 19, 20, respectively. The damper levers 31, 32 project through the apertures 55 for manipulation of the damper 26 from the exterior of the register.

The operation of this register is as follows: The damper 26 may be positioned as shown in full line in Fig. 2, which will cause the air heated by the furnace to discharge substantially equally from the inner casing outlets 22, 23. By pushing downward upon the operating levers 31, 32, the damper 26 will be moved at its lower portion toward that side of the register which has its operating lever depressed. Full depression of either damper lever will move the damper for substantially full cut-off of air flow through that side of the register on which the damper lever was manipulated. When the furnace is operating and heating air, the heated air rising within the furnace partition 9 will rise into the inner casing, a portion being deflected thereinto by the horizontal bottom portions 24 and will discharge through the open passageways 22, 23 and their respective grille apertures 55 into the rooms to be heated. The upflow of air within the partition 9 will draw air downward through the grilles 61 into the passageway surrounding the partition 9, beneath the lower edge of this partition 9, as is well known in the art, and thence upward as above described around the combustion chamber 7 and radiators 8 to the interior of the inner casing 11. Some of the return air will be drawn through the grille openings or slots 54 into the passageways 50, 51, 52 and 53 and thence flow downward with the air entering the grilles 61 to be heated as above described. The air flowing downward through the passageways 50, 51, 52 and 53 provides a layer of cooling air interposed between the heated air in the inner casing 11 and the portions of the wall 4 at the sides of the register receiving opening. The lower top wall 18 of the inner casing will be heated in part by direct radiation from the combustion chamber 7 and radiators 8 and in part by the heated current of air, and therefore the air in the passageways between the upper and lower top walls 17,

18 will be heated and flow outward from these passageways, discharging into the rooms through the upper portions of the grille slots or apertures 55. The air discharging from these passageways will cause relatively cool air from the rooms entering the grille slots 54 to flow through the end wall apertures 25 into the passageways between the upper and lower top wall members 17, 18 to cool these walls and particularly the wall 18, the air entering through the apertures 25 discharging as above described into the rooms through the grille slots 55.

Having thus described the invention, what is claimed and desired to be secured by Letters Patent of the United States is:

1. In a dual wall register, an inner casing having an open bottom, having end walls, having a top wall joined to said end walls, and having side walls extending between said end walls, the upper edges of said side walls terminating below said top wall to provide opposite air outlet openings, an outer casing having an open bottom and having end walls spaced from said inner casing end walls to form air flow passageways adapted to register with an air flow passage, said outer casing end walls extending above said inner casing end walls, a top wall member positioned above said inner casing top wall and joining said outer casing end walls, grille supporting members spaced from said inner and outer casings, means securing said supporting members to said outer casing end walls, said supporting members having grille receiving openings registering with said air outlet openings, said receiving openings overlapping said passageways between said inner and outer casing end walls for air flow into said passageways, and grille members in said receiving openings.

2. In a dual wall register, an inner casing having an open bottom, having end walls, having a top wall joined to said end walls and having side walls extending between said end walls, the upper edges of said side walls terminating below said top walls to provide opposite air outlet openings, an outer casing having end walls spaced from said inner casing end walls to form air flow passageways, said outer casing end walls extending above said inner casing end walls, a top wall member positioned above said inner casing top wall and joining said outer casing end walls, grille supporting members spaced from said inner and outer casings, said supporting members having grille receiving openings registering with said air outlet openings, said receiving openings overlapping said passageways between said inner and outer casing end walls for air flow into said passageways, grille members in said receiving openings, said supporting members having end face portions spaced from said outer casing end walls and having side face portions surrounding said grille receiving openings, flange members extending from said side face portions into overlapping engaging relation with the side edge portions of said outer casing end walls, and means securing said flange members to said outer casing end wall edge portions.

3. In a dual wall register, an inner casing having an open bottom, having end walls, having a top wall joined to said end walls and having side walls extending between said end walls, the upper edges of said side walls terminating below said top walls to provide opposite air outlet openings, an outer casing having an open bottom and having end walls spaced from said inner casing end walls to form air flow passageways adapted to register with an air flow passage, said outer

casing end walls extending above said inner casing end walls, a top wall member positioned above said inner casing top wall and joining said outer casing end walls, vertical partition members extending one from the mid-portion of each outer casing end wall toward the adjacent inner casing end wall to position said inner casing endwise within said outer casing, grille supporting members spaced from said inner and outer casings, means securing said supporting members to said outer casing end walls, said supporting members having grille receiving openings registering with said air outlet openings, said receiving openings overlapping said passageways between said inner and outer casing end walls for air flow into said passageways, and grille members in said receiving openings.

4. In a dual wall register, an inner casing having an open bottom, having end walls, having a top wall joined to said end walls and having side walls extending between said end walls, the upper edges of said side walls terminating below said top walls to provide opposite air outlet openings, an outer casing having end walls spaced from said inner casing end walls to form air flow passageways, said outer casing end walls extending above said inner casing end walls, a top wall member positioned above said inner casing top wall and joining said outer casing end walls, grille supporting members spaced from said inner and outer casings, means securing said supporting members to said outer casing end walls, said supporting members having grille receiving openings registering with said air outlet openings, said receiving openings overlapping said passageways between said inner and outer casing end walls for air flow into said passageways, grille members in said receiving openings, said inner casing side and end walls extending below said outer casing end walls and said supporting members, and horizontal bottom wall members extending outward one from the lower edge of each inner casing side wall and terminating beyond said supporting members.

5. In a dual wall register, an inner casing having an open bottom, having end walls, having side walls with opposed side wall openings and having upper and lower top walls spaced from each other and joined to said end walls, said upper top wall being inclined upwardly in opposite directions from its mid-portion toward said side walls, said end walls having apertures therethrough positioned between said top walls for air inflow to the space between said top walls, an outer casing having end walls spaced from said inner casing end walls and having a top wall spaced above said inner casing top walls, grille supporting members secured to the opposite side edge portions of said outer casing end walls, said supporting members having grille receiving openings registering with said side wall openings and extending laterally therebeyond into overlapping relation to the spaces between said inner and outer casing end walls for inflow of air through said grille openings into said last-named spaces for admission to said apertures, and grille members in said receiving openings.

6. In a dual wall register, an inner casing having an open bottom, having end walls, having side walls with opposed side wall openings and having upper and lower top walls spaced from each other and joined to said end walls, said upper top wall being inclined upwardly in opposite directions from its mid-portion toward said side walls, said end walls having apertures therethrough po-

sitioned between said top walls for air inflow to the space between said top walls, an outer casing having end walls, vertical partition members extending inward from the mid-portions of said outer casing end walls toward said inner casing end walls and spacing said outer casing end-wise from said inner casing to provide air flow passageways, grille supporting members secured to the opposite side edge portions of said outer casing end walls, said supporting members having grille receiving openings registering with said side wall openings and extending laterally therebeyond into overlapping relation to said passageways between said inner and outer casing end walls for inflow of air through said grille openings into said passageways for admission to said

5 apertures, and grille members in said receiving openings.
